UNITED STATES PATENT OFFICE.

THOMAS B. DOOLEY, OF MALDEN, MASSACHUSETTS, ASSIGNOR TO EVERETT D. WIGGIN, TRUSTEE.

MOTOR-VEHICLE.

SPECIFICATION forming part of Letters Patent No. 662,372, dated November 20, 1900.

Application filed March 19, 1900. Serial No. 9,155. (No model.)

To all whom it may concern:

Be it known that I, THOMAS B. DOOLEY, of Malden, in the county of Middlesex and State of Massachusetts, have invented certain new 5 and useful Improvements in Motor-Vehicles, of which the following is a description sufficiently full, clear, and exact to enable those skilled in the art to which it appertains or with which it is most nearly connected to make 10 and use the same.

This invention has relation to "automobiles" or "motor-carriages"—that is, carriages or vehicles that are driven by power in contradistinction to the same means that are 15 ordinarily drawn by horses.

It is the object of the invention to improve the construction of the framework which carries the engine and other parts of the load, so that the latter may remain substantially 20 level and not be influenced as to position by slight variations in the different heights or positions of the wheel.

It is further the object of the invention to "box" the "equalizing" mechanism in a substantial 25 casing and truss the casing from its ends to connections with the axle, so as to stiffen and strengthen all of the connected parts to enable them to accomplish perfectly the functions designed to be secured by them.

30 It is also the object of the invention to provide other improvements in motor-carriages, all as will hereinafter more fully appear.

Reference is to be had to the annexed drawings, and to the letters marked thereon, forming 35 a part of this specification, the same letters designating the same parts or features, as the case may be, wherever they occur.

In the drawings, Figure 1 is a plan view of a motor-carriage embodying my improvements, the body and all other parts not cooperating with my invention being removed, and the same is true of all the other views of the drawings. Fig. 2 is a horizontal sectional view of the rear portion of the carriage-frame 40 embodying my improvements located at or in proximity to the rear axle. Fig. 3 is a vertical sectional detail view showing the manner of trussing the box or casing of equalizing mechanism with means at the ends of the 45 axles supported by the latter, so as to render 50

the parts stiff and rigid and keep them in proper place and alinement under all conditions. Fig. 4 is a front view of the improved means for supporting the vehicle.

In the drawings, *a* designates the frame-work of the running-gear, which framework is composed of tubes, rods, bars, or other forms of means, all preferably composed of metal. The frame supports the cylinders *b b* for operating the driving mechanism, which cylinders are connected by suitable means, as shown, with cranks on the crank-shaft *c*.

The means described so far are a little more than diagrammatic and are meant to equip the carriage so that it may run at varying speeds—that is, at a slow or high speed. Briefly described, the mechanism mentioned consists of a large gear-wheel *d* and a small gear-wheel *e*, running loose on the crank-shaft *c*. Between said two gear-wheels is a 60 clutch-gear *f*, splined on the shaft *c* and driven by it, though adapted by its splined connection to be moved longitudinally on the shaft—a thing that may be done by the forked lever *g* (shown in Fig. 1) operating between 65 the clutch-gears *h* and *i*.

It will be understood that the clutch-gear *f* is provided with means whereby it may become engaged with the gears *d* and *e*—that is, so that when the clutch-gear *f* is moved toward the gear *d* it will become engaged therewith, while the gear *e* will run without effect on the crank-shaft, and when the clutch-gear is moved in the opposite direction it will become engaged with the gear *e* and turn that 85 gear, while the gear *d* will be released to run loose upon the shaft without effect. The said gears *d* and *e* will mesh with gears *j* and *k* on the rear divided axle *l*, upon which axle between the gears *j* and *k* are bevel-gears, constituting the well-known so-called "equalizing" mechanism.

All the parts so far described constitute no part of my present invention and will be readily understood by those skilled in the art 90 without further description.

The inner ends of the divided rear axle extend into and are secured to the bearings consisting of the hubs *m* of the gears of the equalizing mechanism with which they coöperate. 95 100

Each of the said bearings is arranged to run upon antifriction-rollers n , arranged in a box o , having its outer surface rounded as though it formed the central segment of a sphere and having side or end pieces p screwed in the sides to keep the rollers. The outer surface of this segment of a sphere o has correspondingly-shaped bearings formed in the box or casing q , inclosing the equalizing device and supporting the same and all connections with the inner ends of the divided shaft or axle. The outer ends of the divided axle are constructed and operate in bearings similar to that of the inner ends. Instead, however, of the boxes o being supported by the casing q they are sustained in the center of disks r adjacent to the wheels.

The casing q is braced and supported by means of rods t , the rods extending between the said casing and the disk r , the ends of the rods being screw-threaded and provided with nuts, as shown, whereby the latter may be turned up and so brace and secure the casing q in rigid position and also hold the disks r rigid and so stiffen the frame and all parts connected with the casing q and bearings for the divided axle l . From the hub of the disk r there extend forward toward the front wheels suitable tubes or rods to form the frame. (Best shown in Fig. 1.) The form and construction of the said rods are best shown in Fig. 3, where one rod u extends upward and forward from the hub r , while another rod v extends directly forward in a horizontal line, the two rods being braced at suitable points by connections between them, as indicated at w . These rods u and v are made tubular for part of their lengths and are connected with solid parts, as shown in Fig. 3, by having branches of the solid parts extend into the tubular parts of said rods. In addition to the side rods or tubes u v the structure at or about the rear axle l has cross rods or tubes connected with the side rods, so as to render the parts still more rigid at this point.

Under the construction thus far shown it will be observed that the construction and bracing of the box q and connected parts not only secures stiffness, rigidity, and proper alignment of the shafts, bearings, gears, &c., but should undue strain come upon the rear axle, which would tend to impart torsional or other undue strain on the gears, the bearing o , which in its relationship to the frame is to all intents and purposes a ball-bearing, will yield, so that the rollers n will not become bound in their supports, and, in fact, so that none of the operative parts of the motor will be detrimentally affected by unequal or undue strain on the wheels and axle. In other words, ample and efficient "give-and-take" means for taking up the "wave" motion of the body when the wheels are running over uneven surfaces is provided. It will be understood that the "ball-bearing" connec-

tion between the frame and rear axle consists of a ring formed as the central segment of a sphere, the external bearings for the ring corresponding with the form of the latter, the axle passing through the sleeve m and the rollers n surrounding the sleeve between the latter and the inner surface of the ring.

The manner of supporting the equalizing device and its connections at the center of the divided axle through the medium of the rods t and disks r is also considered of importance in this invention.

I may next describe the connection of what has already been explained fully with the front wheels and a steering apparatus, the connection being through the medium of the frame-rods a . It may be stated, however, that while the steering mechanism is fully described it forms no part of my present invention.

The frame-rods a extend from the front to the rear axle. At their front ends they are secured to the cross or bolster bar y , provided at each of its ends with a thimble z , through which a bolt extends, said bolt being connected at its lower end to the axle-support a' and having a bevel-gear b' or it may be a bevel-toothed segment secured to its upper end.

c' is a shaft provided on each end with a bevel-gear d' , which meshes with its respective gear-wheel b' . The shaft c' is provided with bearing $e' e'$, formed on the upper ends of the brackets $f' f'$, secured at their lower ends to the cross-bar y .

g' represents the wheel-spindles, (shown as broken off in Fig. 4,) which are formed on the outer ends of the axles h' , fixed in the supports a' . The said spindles g' , it will be understood, are constructed so that the front wheels of the carriage may turn thereon. A lever i' is secured to the shaft c' and extends upward to an appropriate point, so that by moving the said lever forward or backward the axles, spindles, and axle-supports will be swung around in one direction or the other through the medium of the gears d' , shaft c' , and gears b' and their bolts extending through the thimble-bearings z .

In some places in the drawings portions are represented as broken away to show preferable, though not essential, forms of construction. Figs. 1 and 2 give a clear understanding of the construction of the frame when viewed from above, while Fig. 3 does the same thing when the frame is viewed from the side.

It will be understood that the part o , its bearing, and means coöperating therewith, which have been referred to as a "ball-bearing," operate somewhat on the principle of a universal joint, and any means accomplishing this same result will be regarded as coming within the limit or scope of the invention.

Having thus explained the nature of the invention and described a way of constructing and using the same, though without attempt-

ing to set forth all of the forms in which it may be made or all of the modes of its use, it is declared that what is claimed is—

1. A motor-vehicle frame provided with a centrally-divided axle, each inner and outer end of each divided part having bearings arranged in a box having its outer surface rounded to permit it to rock and brace-rods *t* between the bearings to stiffen and support them, as set forth.

2. A motor-vehicle frame, in combination with the divided axle of the vehicle, an equalizing mechanism thereon, a casing inclosing the said mechanism, disks *r* on the outer ends *15* of the axles, and bracing devices between the casing and disks, substantially as disclosed.

3. A motor-vehicle frame, in combination with the divided axle of the vehicle, an equalizing mechanism thereon, a casing inclosing *20* the said mechanism, disks *r* on the outer ends of the axles, and bracing devices between the casing and disks, and a ball-bearing connection of the frame with the axle, said ball-bearing connection being arranged at points *25* coincident with the sides of the casing and said disks, substantially as disclosed.

4. In a vehicle, the combination of a frame; a divided axle; wheels thereon; equalizing-gearing connecting the inner ends of the axle *30* members; a casing for said equalizing-gear-

ing; and bearings for the axle members having rounded exterior surfaces engaging said casing.

5. In a vehicle, the combination of a frame, a divided axle; wheels thereon; bearing for *35* the outer ends of the axle members with rounded exteriors engaging the frame; equalizing-gearing connecting the inner ends of the axle members; a casing inclosing the equalizing-gearing; and bearings for the inner ends *40* of the shaft members having rounded exteriors engaging the said casing.

6. In a vehicle, the combination of a frame; a divided axle; wheels thereon; bearings for *45* the outer ends of the axle members with rounded exteriors engaging the frame; equalizing-gearing connecting the inner ends of the axle members; a casing inclosing the equalizing-gearing; and brace-rods extending between the latter and the portions of the frame *50* engaged by the bearings for the outer ends of the axle members.

In testimony whereof I have signed my name to this specification, in the presence of two subscribing witnesses, this 29th day of *55* January, A. D. 1900.

THOMAS B. DOOLEY.
